METHOD OF MAKING CONTAINERS

George Arlington Moore, Louisville, Ky., assignor
to Humoco Corporation, Louisville, Ky., a corporation of Delaware

Application May 26, 1937, Serial No. 144,842

8 Claims. (Cl. 93—39.1)

This invention relates to containers and more particularly to containers comprising fibrous materials and to methods and means for fabricating the same and making the component parts thereof.

One of the objects of the present invention is to provide a novel container which may be commercially fabricated from flexible materials, such as paper, fibre board, foil and the like.

Another object of the invention is to provide a novel method and means for making containers and sealing the same whereby containers which are substantially impervious to air and moisture may be fabricated by automatic machinery capable of securing rapid production in large quantities at low cost.

Another object is to provide a novel container wherein products and particularly hygroscopic products, such as tobacco, for example, may be sealed and retained for an indefinite period without noticeable change in the condition of the packaged product irrespective of the temperatures, pressures and climatic conditions to which the package is subjected.

Still another object is to provide a novel metallized fibrous container which is so constructed that the same may be readily and cleanly opened by digital pressure.

A further object is to provide a container wherein a novel seam is provided for joining the container body and a closure member therefor, whereby said container may be rendered substantially impervious to air and moisture.

A still further object is to provide a novel method of applying a thin coating of liquid to a predetermined area of the inner wall of a tubular container or the like whereby an adhesive coating thereon may be activated without danger of removing said coating or contaminating other parts or the contents of the container.

Another object is to provide a novel method and means for forming grooves in the walls of a container body and for supporting the same while inserting a closure member therein, and curling the body wall inwardly to secure said closure in position.

Another object is to provide a tubular container body which is constructed from a plurality of blanks having the ends thereof joined by lap or butt joints and which comprises novel means for improving the moisture-proof character of at least one of said joints.

The above and further objects and novel features of the invention will more fully appear from the following detailed description, when the same

is read in connection with the accompanying drawings. It is to be expressly understood, however, that the drawings are for the purpose of illustration only and are not intended as a definition of the limits of the invention, reference being had for this latter purpose to the appended claims.

In the drawings, wherein like reference characters refer to like parts throughout the several views,

Fig. 1 is an isometric view of a preferred form of cover for the container;

Fig. 2 is an isometric view, partly in section, of the upper head of the container before it is inserted into the container body or shell;

Fig. 3 is an isometric view showing the container shell or body after the initial steps in the fabrication thereof;

Fig. 4 is an isometric view, partly in section, of the lower or bottom head of the container prior to its insertion into the shell;

Fig. 5 is a side elevation, partly in section and with parts broken away, illustrating one form of container embodying the present invention, the contents having been removed from the upper end thereof and the cover being shown in open position;

Fig. 5a is a sectional view taken substantially on line 5a—5a of Fig. 5;

Fig. 6 is a diagrammatic top plan illustrating means for carrying out the novel method of applying a liquid to the inner surface of the shell of Fig. 3;

Figs. 7, 8 and 9 show various forms of blanks, on a reduced scale, which may be employed in making the heads of Figs. 2 and 4;

Fig. 10 is a plan view, partly in section and with parts broken away, showing one embodiment of the novel rib forming and body supporting means employed in carrying out the novel method of the invention, the parts being shown in expanded and contracted positions in the left and right halves of the figure, respectively;

Fig. 11 is a similar view illustrating means which are not satisfactory for practicing said method;

Fig. 12 is a similar detail view showing one of the die members of Fig. 10 as the same initially engages the container body;

Fig. 13 is a top plan view similar to the right half of Fig. 10 with one segment of the die removed;

Fig. 14 is a detail side elevation, partly in section and with parts broken away, showing the

mechanism for performing the initial step in the formation of the closure seam;

Fig. 15 is a similar view of means for completing said seam;

5 Fig. 16 is a diagrammatic isometric view of means for applying an adhesive activated liquid to the paper laminae of the body and for applying a paraffin treated strip thereto;

Figs. 17 and 18 are detail sectional views, with 10 parts broken away, of a partially completed body showing novel means for impregnating a lap joint with paraffin or the like;

Fig. 19 is a detail sectional view, on an enlarged scale, the section being taken through a 15 completed container in a plane corresponding to the line 19—19 of Fig. 18;

Fig. 20 is a detail view, partly in section and with parts broken away, of suitable means for forming the head shown in Fig. 2;

20 Fig. 21 is a rear elevation, with parts broken away of the container of Fig. 5;

Fig. 22 is a side elevation of a portion of said container;

Fig. 23 is a sectional view, with parts broken 25 away, taken on line 23—23 of Fig. 21; and,

Fig. 24 is a side elevation, partly in section and with parts broken away, showing means for inserting a closure in the body, the section being taken in the plane of line 24—24 of Fig. 13.

30 One embodiment of the container of the present invention is illustrated in the drawings, by way of example, in the form of a container suitable for packaging tobacco, the same being so constructed as to prevent escape or absorption 35 of moisture from or by the tobacco or other contents of the container, thereby insuring that the consumer will receive said contents in factory-fresh condition. The container is also so constructed as to be readily opened by digital pressure without the aid of tools of any kind for the 40 purpose of dispensing the contents as the use of the same is desired. Preferably, the container is metal-lined and the component parts thereof are secured together by metal-to-metal seams having 45 adjacent surfaces joined by a non-hygrosopic lacquer in a novel manner to hereinafter appear. Novel means are also incorporated in said container to obviate wicking of moisture from the tobacco into or through the paper component of 50 the body or shell.

In the form shown, said container comprises a laminated shell or body 2 (Fig. 3) having straight parallel side wall portions 2a connected by arcuate end wall portions 2b. This shell may be formed by wrapping one or preferably a plurality of rectangular blanks of suitable material, such as paper and foil, about a mandrel (not shown) which is preferably expansible and collapsible and which has an uninterrupted periphery when expanded. When a plurality of blanks are employed, the same are applied to the mandrel one at a time in succession and contiguous blanks are adhesively secured together throughout the areas thereof. The ends of each of said 65 blanks overlap at arcuate wall portions 2b and are adhesively secured together, the lap joints of contiguous blanks being formed at opposite sides of the shell. The body may also be formed by wrapping a single blank about the mandrel 70 several times and butt joints may be employed in lieu of said lap joints, if desired.

Although any suitable numbers of laminations may be employed, shell 2 is shown as having a three-ply wall, the inner lamina 3, 4 (Fig. 19) being constituted by a blank having an inner

layer of metallic foil 3, preferably with a thickness of from .00035 to .0005 inch, adhesively secured to a layer of paper or like material 4. For adhesively joining the overlapping ends of blank 3, 4 and for other purposes to appear hereinafter, 5 the entire surface or selected areas of layer 3 of the inner lamina may be precoated with a thin, dry film of acetate lacquer, or other suitable substance, indicated by stippling in Fig. 3, which has potential adhesive properties and is adapted to 10 be activated by either heat, a solvent, or both. Said lacquer should be non-hygrosopic and so constituted as to adhere readily to the foil and constitute a good binding medium either in a foil-to-paper or a foil-to-foil seam or joint. One 15 cement or lacquer which has been found suitable for this purpose is Reynolds Metals Company acetate lacquer No. TC-3. This particular substance is a clear lacquer which becomes plastic or tacky at about 350° F. or more, is neutral when dry, 20 is soluble in alcohol or acetone and is adapted to be readily applied to the foil in a thin, dry film by a roller coating method. When the entire surface of foil layer 3 is coated, it has been found that satisfactory results may be obtained by 25 using from 2 to 4 pounds of lacquer per ream of material.

In forming shell 2, the blank 3, 4 is first wrapped around a mandrel (not shown) with layer 3 innermost and a lap joint 5 is formed 30 between the overlapping ends of blank 3, 4, as best seen in Figs. 17 and 18, said ends being pressed together by a sealing tool, such as iron 6, which is heated by a pair of electric cartridge heaters 7 or any other suitable means thermostatically controlled through a thermostat bulb 1a. The heat from said iron is effective to activate the lacquer coating on the surface of foil layer 3 and the pressure exerted thereby presses the activated lacquer into the interstices of the 40 engaging surfaces, thereby substantially welding the same together. The pressure applied by tool 6 is preferably sufficient to compress the paper component of the blank at its overlapped ends, thereby forming a tapered joint and causing the 45 end of foil layer 3 within body 2 to engage an intermediate portion thereof, as at 8 (Fig. 17), and thus provide said body with a substantially continuous inner surface of impervious non-hygrosopic foil. The compression of paper laminations 50 4 in joint 5 also materially reduces the wicking effect thereof and accordingly the passage of moisture into and out of the container through this portion of the joint.

The blanks from which shell 2 is made are 55 preferably cut from continuous strips, such as strip 9, illustrated in Fig. 16, for example, and the paper strip constituting the second or filler lamina 10 (Fig. 19) is coated on the inner surface with a dry film of a suitable gum or adhesive which may be activated by the application thereto of a small quantity of water or other activating liquid by any suitable means, such as rollers 11 and 12, the former of which rotates in a vessel 13 containing said liquid. For a purpose to appear hereafter, a narrow strip 14 of paper or other suitable material having the upper or outer surface thereof, as viewed in Fig. 16, coated with paraffin or other moisture-repellent substance is adhesively secured to the 70 center of strip 9 before the latter is cut into blanks of the desired length. Thus, when blank 10, 14 is wrapped around the forming mandrel, with the adhesive-coated surface thereof in engagement with lamina 3, 4, the wax-coated sur- 75

face of strip 14 is brought into contact with joint 5 (Fig. 17). Pressure and heat are then applied to the arcuate wall of the partially completed shell by means of iron 6, thereby melting the paraffin and causing the same to impregnate the ends of the paper component of the inner lamina 3, 4 in the manner indicated by heavy hatching or shading in Fig. 18. The raw edges of paper layer 4 are thus rendered moisture repellent and will not absorb or wick moisture to or away from the contents of the completed container. As heretofore pointed out, the compression of said edges during the formation of joint 5 also assists in preventing absorption of moisture thereby. It will be understood that a satisfactory joint 5 could not be formed if the ends of the paper layer were impregnated with wax prior to the formation of said joint, since wax has no affinity for the thermoplastic lacquer employed or other adhesive substances.

The third or outer lamina 15 (Fig. 19) is also coated with a suitable adhesive and secured to lamina 10 so that the lap joints of the contiguous blanks are at opposite arcuate ends of the shell. Lamina 15 may have any desired printed matter impressed thereon for advertising purposes or the like and the outer surface may be coated with a thin film 16 of high-gloss lacquer. The latter improves the appearance of the container and renders the outer surface thereof water repellent. If desired, the outer surface of the container may be constituted by a thin layer of metallic foil in lieu of or in combination with the high-gloss lacquer film 16. If an outer layer of foil is employed, the same is preferably secured to paper lamina 15 by a suitable solvent activated lacquer. It will be noted that in certain views the body and closures therefor are, in the interest of clarity, shown as having a single thickness instead of being laminated.

While shell 2 is still on the forming mandrel and before the adhesives between the laminations are completely dry, internal ribs 17 and complementary external grooves 18 extending parallel to the ends of the shell (Fig. 3) are drawn in each of the straight side walls 2a. For this purpose, said mandrel may be provided with grooves in the sides thereof, and external dies having portions adapted to register with said grooves may be pressed into contact with the walls of the shell and thereby draw or press portions of said walls into rib formation. Ribs 17 may be of any suitable shape but the same preferably comprise a ledge portion 17a extending at substantially right angles to walls 2a, an intermediate portion 17b parallel to said walls and a portion 17c making an angle of approximately 45° with said walls. These ribs tend to stiffen and strengthen body or shell 2 and serve other purposes which will more fully appear hereafter.

By drawing rib 17 before the adhesives between the laminations of the shell become bone dry, some slippage between said laminae is permitted when sufficient pressure is applied for the drawing operation. Said adhesives are sufficiently dried, however, to be effective for holding the layers or laminae against slippage merely by the forces tending to cause the deformed material to spring back to its original position after removal of the drawing dies. Said ribs may thus be formed and rendered permanent without exceeding the elastic limit of the materials being deformed. The strength and texture of said materials is also maintained and the impervious nature thereof is not affected. Suitable apparatus

for drawing ribs 17 is illustrated in a number of applicant's copending applications, such as in application Serial No. 53,722, filed December 10, 1935.

After the formation of ribs 17 and complementary grooves 18, the mandrel on which body 2 is formed is collapsed and said body is removed therefrom and taken to a station at which novel means are employed for activating a predetermined area of the lacquer film on foil layer 3 whereby an end closure may be adhesively secured therein in a novel manner to hereinafter appear. As illustrated by heavy hatching in Fig. 3, a peripheral portion or annular band 19 extending from the ledges 17a of ribs 17 to a line adjacent the edge of body 2 is activated, the activating agent being applied by a roller 20 (Fig. 6), the axial length of which is equal to the desired width of band 19. In order to prevent the thin lacquer coating from being wiped off of foil layer 3 by the action of roller 20, the latter is mounted and caused to rotate about its own axis and said axis is constrained by suitable cam means to travel in a path indicated by line 21 during rotation of the roller. The roller thus has rolling contact only with the shell wall, thereby eliminating any tendency thereof to rub the lacquer coating from said wall. If desired, the axis of rotation of roller 20 may be fixed and the shell wall frictionally clamped between the same and another roller (not shown) mounted exteriorly of the shell whereby, upon rotation of the cooperating rollers in opposite directions, the shell itself is rotated.

For the purpose of preventing any washing of the lacquer film from foil layer 3 by the activating agent and for obviating the too rapid drying thereof, the activating liquid applied by roller 20 is preferably a liquid lacquer containing solids which is constituted similar to the dry film being activated. When an acetone solvent or the like is employed as an activating agent, the same evaporates so quickly that the surface becomes dry before the head of Fig. 2 can be conveniently inserted and secured in the body in the desired manner. This is particularly true when the solvent is used in sufficiently small quantities to prevent the same from dissolving or washing off the thin lacquer film and running onto other parts of the shell wall, and, hence, from causing contamination of the machinery employed and the product with which the container is filled or is to be filled.

In a container of the shape illustrated, the side walls 2a have a tendency to bow inwardly, as shown in Fig. 11, and the dies, one form of which is shown in Fig. 11, heretofore employed for supporting body 2, during the insertion of end closures therefor, have exerted forces on said body tending to increase this bowing. When sides 2a bow inwardly in this manner, the same obstruct the insertion of the closures and, as will be hereinafter more fully pointed out, prevent the proper curling of the body wall margins to lock the closures in position within said body. Novel means are accordingly provided whereby suitable forces are applied to the walls of body 2 by supporting means therefor which tend to cause side walls 2a to bulge outwardly instead of inwardly. In the form shown, said means are constituted by a set of die members that cooperate to form a collapsible and expandable female die, which is effective, when collapsed, to form internal ribs 17' and complementary external grooves 18' in the arcuate end walls 2b, which ribs 75

and grooves may constitute extensions of ribs 17 and grooves 18 previously formed in side walls 2a.

Said collapsible die, as illustrated, comprises a pair of linearly movable members 22, 22 provided with inwardly extending ribs 23 which are adapted to register with grooves 18. The end portions of members 22 above ribs 23 are preferably extended a short distance around arcuate walls 2b but are cut away below the plane 10 of the upper surfaces of said ribs to provide recesses 22a for the reception of the lower portions of die members 24, 24. The upper portions of the latter members cooperate with the upper portions of members 22 to form a die having an uninterrupted periphery when collapsed which engages the outer wall of the marginal portion of shell 2 above rib 17, 17' (Fig. 13a). The lower and somewhat enlarged portions 24a of members 24 extend into recesses 22a formed 15 in members 22 and are so formed as to engage the entire surface of end walls 2b over an area below rib 17'. The upper edge of each of the portions 24a constitutes a rib 24b which is effective to form ribs 17' in the body of shell 2. The 20 shell is preferably subjected to the action of dies 24, 24 before the adhesives between the laminations thereof are completely dry in order that some relative slippage of the layers may occur during the formation of grooves 18' for reasons 25 fully pointed out above in connection with the drawing of grooves 18.

In subjecting the shell to the action of die 22, 24, one end of said shell is inserted in the die while the latter is in expanded position, as shown 30 in the left half of Fig. 10. The die is then moved to closed position by any suitable means well known in the art, such as means including a wedge member 25 (Fig. 24) which cooperates with suitably inclined portions of the die members. It will be seen from Figs. 10 and 12 that 35 the slightly rounded ends of rib 24b on members 24 engage the shell first at such points that the pressure exerted thereby is effective to cause side walls 2a to bow outwardly toward members 22, as indicated at the top of Fig. 13. As die members 24 move inwardly in the direction of the arrows, grooves 18' and ribs 17' are progressively drawn in curved walls 2b by ribs 24b, the pressure of said die members being resisted 40 by the rigidity of walls 2a. An inwardly directed pressure is thus applied entirely around said walls 2b which tends to cause the shell to assume a circular contour and, hence, hold walls 2a in firm engagement with members 22 throughout 45 the length of said walls. It will be noted that, in forming ribs 17', the radius of curvature of the material constituting the rib is reduced. A portion of the excess material is blended into ribs 17, previously formed in side walls 2a, and rib 50 17' is rendered comparatively smooth by the fact that the same is drawn by member 24 progressively from opposite ends toward the center of side wall 2b. If desired, the free end of the shell may be supported during the formation 55 of ribs 17' by any suitable means, such as a chuck, one form of which is shown in my co-pending application referred to above. Said means may also be employed for moving the shell from one station to another, at which the various steps in the fabrication of the container are 60 carried out.

While shell 2 is held against longitudinal movement by die 22, 24 with the marginal walls thereof in firm engagement with the inner walls 65 of the die, a flanged closure member or head 26

(Fig. 2), constituted in a novel manner to hereinafter appear, is inserted in said body by a male die 27, 27a (Fig. 24) that pushes said head or closure through a female die 28 which has an opening that registers with die 22, 24. The periphery of the upper or inner end of the latter die is preferably reduced somewhat to form a shoulder 29 having a radial width substantially equal to the wall thickness of shell 2 (Fig. 24). Thus, any possibility of the head's striking the 10 edge of body 2 during the insertion of the former is obviated.

As head 26 is moved into body 2, the flange 26a thereof engages the activated ribbon of lacquer 19 on the inner wall of the marginal portion of said body and is effective to push some of said lacquer down onto ledge 17a of rib 17, 17' and, hence, adhesively join the base of the head and said ledge (Fig. 19), the pressure exerted by the head inserting male die 27, 27a 15 being effective to press the activated adhesive into the interstices of the surfaces of said base and ledge. When closure 26 is seated on rib 17, 17', the inserting die is withdrawn, portion 27a thereof being effective to strip the closure from 20 portion 27, die 22, 24 is expanded, and the headed shell is moved to another station at which the head is secured in position by flowing the marginal portion of the shell into overlapping relation 25 with flange 26a of said closure. 30

For this latter step, the headed end of the shell is inserted in an expandable female die comprising a member 30, said die being similar to die 22, 24 except that no shoulder corresponding to shoulder 29 is provided and, for a purpose to 35 hereinafter appear, the upper or pressure opposing surfaces of ribs 30a corresponding to rib 23, 24b incline inwardly toward the wall of the die, as best seen in Fig. 14. The lateral pressures exerted by the members constituting die 30 are 40 effective to bow the sides of walls 2a into firm engagement with the inner surface of the die, in the same manner as pointed out above in connection with die 22, 24. Head 26 which has been inserted or bottom closure 31 (Fig. 4), depending on which end of the shell is being closed, 45 assists in this latter function.

While the headed shell is thus supported and held against longitudinal movement, a male die 32 having an arcuate peripheral groove 33 formed 50 in the lower face thereof is moved into die 30 and into engagement with the edge of shell 2 by any suitable well-known means. Further downward movement of die 32 is effective to curl or flow the marginal portion of the shell into overlapping or interlocking relation with flange 26a 55 of head 26, as indicated by dotted lines in Fig. 14, the raw edge of said marginal portion being directed into a peripheral groove 26b bounded by said flange and an arcuate rib portion 26c 60 that joins the flange and central portion of head 26. It is important, during the curling or flowing operation, that side walls 2b of the shell be held in firm engagement with the walls of die 30, since, if the same bow inwardly, as indicated 65 in Fig. 11, the wall will not flow freely along the surface of groove 33 and the pressure of die 32 will be so directed as to crush instead of curl the same. Ribbon 19 of activated lacquer is preferably of sufficient width to extend upwardly 70 beyond the upper edge of flange 26, so that when the curling action is completed, some of the activated adhesive will engage the inner surface of said flange (Fig. 19).

In order to obviate any danger of the shell's 75

slipping relative to die 30 during the curling of the margin of said shell, the upper surface of rib 30a is sloped downwardly toward the inner wall of the die. As pressure is applied to the 5 edge of the wall of the shell by die 32, ledge 17a of rib 17, 17' yields and tends to conform itself to the upper wall of rib 30a, in the manner indicated in Fig. 15, and thus more firmly holds the shell against movement and any tendency to 10 collapse. The greater the pressure exerted against the end of the shell by die 32, the greater will be the holding effect of rib 30a.

Shell 2 is next moved to a station where the headed end thereof is again gripped by an expandible female die comprising member 34 (Fig. 15) while the closure seam is compressed by the application of laterally directed pressure thereto. Said pressure is exerted by an expandible 15 male die comprising a member 35, said die being expanded by upward movement of a wedge member 36 and, when so expanded, engages the curled portion of the shell margin entirely around the periphery of the container. Die 35 is thus effective to squeeze the excess of material in said 20 curled portion which is held against upward movement by a shoulder on die 34 into groove 26b and to press the engaging surfaces of the shell and flange 26a into firm engagement, thereby by pressing the activated lacquer 19 therebetween into the interstices of the engaging surfaces at 40 and 41 to substantially weld the same together and form an impervious seam or joint. Said seam is thus protected by the burying and anchoring of the raw edge of the shell in groove 25 26b against accidental destruction and against weakening thereof by moisture, which would otherwise enter through said raw edge.

It will be understood that, by providing heating means in the dies of Fig. 15, the above- 40 described closure seam may be sealed by the application of heat and pressure thereto, the heat being employed as the activating agent for the lacquer film on the engaging surfaces of the head and body in lieu of the liquid applied by 45 roller 20. Heat may be more advantageously used in sealing large containers than in sealing small ones, since, with small containers, it is difficult to get the necessary hot irons into the desired positions.

50 Head 26 is preferably formed by subjecting a flat laminated blank 37 to an embossing and drawing operation, the inner lamina 38 of said blank being constituted by metallic foil, such as the inner layer 3 of body 2, and the outer lamina 39 being constituted by a fibrous material such as "Fiberlec," for example, which will stand deformations without fracture. Said laminae are secured together by means of an elastic adhesive, such as one having a latex base, and are 55 preferably coextensive, as shown in Fig. 7, the foil lamina being coated with a thin film of dry lacquer of the same character as that on the inner surface of body 2. Thus, when said head is sealed in shell 2, the closure seam comprises 60 a sealed metal-to-metal joint at 40 (Fig. 19), thereby insuring impermeability. If desired, the seal or joint at 41 may also be made metal-to-metal by providing head 26 with an outer foil lamina 42. The latter also improves the appearance of the head and prevents fiber layer 39 from becoming saturated with moisture. As will more fully appear hereinafter, the central portion of head 26 is scored to provide a hatch 65 whereby an opening for dispensing the contents

of the container may be readily made by digital pressure.

In forming head 26, the blank 37 is placed over the opening of a female die member 43, only a portion of which is shown (Fig. 20), and yielding held in position to be engaged by a male die 44 which carries a relatively movable stripper member 45 and cooperates with a hydraulically backed buffer die 46, the face of which is initially in alignment with the left face of female 10 die 43. As die 44, 45 is moved to the right, as viewed in the drawings, a peripheral arcuate bead 47 thereon engages blank 38, 39 and draws the material of the marginal portion thereof into a peripheral arcuate groove 48 in the face 15 of die 46 to thereby form rib 26c and complementary groove 26b of the head (Figs. 2 and 20).

During the formation of groove 26b, the outer face of the blank is contacted by a cutting knife 49 which is removably mounted in die 44 and projects from the face thereof. Said knife preferably extends completely around the face of die 44 adjacent the inner edge of bead 47 and a section of the cutting edge thereof has the outline of a scalene triangle. In order to prevent 25 the cutting edge of knife 49 from destroying the moisture proof qualities and impermeability of foil lamination 38, the pressure on the face of the blank opposite said cutting edge is relieved by the provision of a similarly shaped groove in 30 buffer die 46, thus preventing any ruptures of the materials by reason of the compression thereon and permitting the central portion of dies 44 and 49 to contact the blank before said knife cuts entirely through the same. Thus, 35 when blank 47 is moved into contact with die 46 by die 44, 45, a furrow 50 is cut around the central portion of head 26 thereby providing said head with a hatch whereby an opening for dispensing the contents of the container may be 40 made by digital pressure, said hatch being formed without destroying the impermeability of the head. If desired, furrow 50 may be cut in blank 38, 39 before the same is drawn into closure form. It will be understood also that said furrow may 45 extend for only a portion of the periphery of head 26 and the same is accordingly omitted in Figs. 14, 15, 23 and 24.

To further facilitate the opening of the container, a plurality of outwardly extending ribs 50 51 (Fig. 2) which constitute bending lines or hinge means for the hatch and buttons 52 which constitute means for readily locating the proper point for application of pressure are embossed in head 26 by means of suitable contours or 55 insets, such as plug 53, projecting from the face of die 46 and adapted to cooperate with suitably shaped recesses in the face of stripping die 45.

Further movement of die 44, 45 into die 43 is effective to draw the entire margin of blank 38, 60 39 into the latter die to thereby form the smooth continuous flange 26a of head 26. The acetate lacquer coating on foil lamina 38 acts somewhat as a lubricant between the blank and the drawing dies thereby facilitating the drawing operation. Said lacquer also serves to assist in preventing oxidizing of the foil and to prevent the foil from flaking during the deformation thereof. Bottom closure 31 (Fig. 4) may be formed in the same manner as head 26 but is preferably formed 70 without the hatch and associated deformations.

Although blanks of the character shown in Fig. 7, i. e., ones in which the areas of the fibrous and foil laminae are coextensive, are preferably used in order to provide foil-to-foil joints or 75

welds in the closure seam, it will be understood that moisture in the activated lacquer is between the engaging surfaces of the shell and flange of the head must evaporate and escape before the lacquer can become dry and set. The foil to which said lacquer is applied is non-hygrosopic and the evaporating moisture must therefore escape between rib 17 and the base of the head rib 26c and, thence, through the open end 10 of the container and/or through head groove 26b. This is a comparatively slow process and accordingly, when it is desired to fill the container immediately or very soon after the insertion of head 26, the latter may be made from the types 15 of blanks illustrated in Figs. 8 and 9 wherein a marginal portion of the fiber lamina 39 is not foil coated. The moisture remaining in the activated lacquer, when heads made from such blanks are employed, is absorbed by the uncoated fiber 20 lamina and, hence, more rapid production may be obtained. For this latter purpose, the blank of Fig. 9, i. e., a blank wherein the foil lamina 38a is applied only to the central portion of the blank, is preferred, but the blank of Fig. 8, 25 wherein a strip of foil 38b, which is narrower than the fibrous lamina 39, is employed, simplifies the application of the foil to the fiber. A section through a closure formed from the blanks of Figs. 8 and 9 is illustrated in Fig. 15.

30 After head 26 is secured in one end of shell 2, the container is filled by inserting the desired contents 54, such as tobacco, through the bottom or open end thereof. During the insertion of the tobacco or other commodity, the inner wall 35 of the marginal portion of shell 2 at said open end is preferably protected from contamination and the tobacco is prevented from lodging on rib 17, 17' by means of a suitable tubular shield (not shown) and said tobacco is held in packed 40 condition by a secondary closure member 55 (Figs. 5 and 5a). The latter is constituted by a flat blank of comparatively stiff yet yieldable material, such as fibre-board and is substantially the same size and shape as shell 2 in cross-section. The yieldable character of closure 55 permits it to be flexed and pushed inwardly through the above-mentioned shield beyond rib 17, 17' whereupon it springs back to substantially normal flat condition and is held in position by said 45 rib. The pressure exerted on the inner face thereof by the sponge action of the packed tobacco or other commodity being insufficient to flex said closure and move the same past said rib. During the insertion of closure 55, shell 2 may be 50 supported by a female die having ribs extending into groove 18, 18' to hold said shell against movement and to absorb the lateral pressure to which ribs 17, 17' are subjected.

The lacquer film on the inner surface of the 55 bottom margin of the shell may then be activated by a liquid lacquer applied thereto by means of roller 20 in a manner heretofore pointed out and the primary bottom closure 31 may be inserted and sealed in place in the same manner described 60 above in connection with head 26. If a foil-to-foil seam is employed, moisture which escapes into the container during the drying of the lacquer or other suitable adhesive or binding medium will be absorbed by the fiber packing disc or closure 55.

70 A cover 56 (Fig. 1) may be hingedly secured to the upper end of the container either before or after the latter is filled with contents 54. Said cover is provided for maintaining said contents in the container after the hatch in head 26 has 75 been broken by the consumer. In the embodi-

ment shown, said cover is formed from a blank comprising fibrous material by subjecting the latter to the action of drawing dies and comprises a central portion (Fig. 23), a peripheral rib 56a to give strength and rigidity thereto and to provide a complementary groove adapted to yieldingly receive the edge of the closure seam, a tab 56b extending downwardly at the back thereof and a downwardly extending flange 56c around the front and sides thereof, said flange being 10 cut away adjacent tab 56b to permit ready opening of the cover and to provide clearance for the pouring and discharge of the contents from the container. Tab 56b has a rib 57 which is adapted to register with groove 18 on the back of body 15 2 and a somewhat smaller rib 58 adapted to fit into a groove pressed into the upper portion of the closure seam as best seen in Fig. 23, and serve as a bending line or hinge for the cover. An internal rib 59 and complementary internal 20 groove may be pressed in flange 56c for cooperation with a rib 60 (Fig. 5) in the closure seam to yieldingly hold the cover in closed position. Rib 60 and the groove into which rib 58 is adapted to extend may be formed by providing 25 suitable ribs and cooperating grooves on pressure dies 34 and 35 of Fig. 15. Cover 56 may be secured to shell 2 by a suitable adhesive which is applied between tab 56b and the area indicated by construction lines in Fig. 3. Preferably, the 30 cover is also secured to the body by means of wire stitching along bending line 58 or by a plurality of wire staples 61 which extend through tab 56b and the adjacent portion of the closure seam. When the hatch in closure 26 has been broken 35 and cover 56 pivoted to the position illustrated by dotted lines in Fig. 22, the contents of the container may be readily poured therefrom. If it becomes necessary to loosen the packed contents of the container this may be done by flexing the body walls without reaching inside of the container as is necessary when tin or other rigid material is employed.

There is thus provided a novel container and method and means for making the same, said 45 container being adapted for use in packaging products and particularly hygroscopic products, such as tobacco, for distribution and sale and being so constructed as to maintain the moisture content of said product substantially 50 constant for an indefinite period of time, thereby insuring that the consumer will receive the same in factory-fresh condition. Additionally, a strong and durable container is provided which may be fabricated from comparatively inexpensive, light-weight materials and is so constructed as to be readily opened without the use of tools and without destroying the usefulness of the container for retaining the contents under all conditions of use. In one form a completely metal-lined 55 fibrous container having metal-to-metal seams formed with a non-hygroscopic cement is provided. A novel method is provided whereby containers of the above character may be efficiently and rapidly manufactured by high-speed, 60 automatic machinery at low cost, said method including novel steps for applying an adhesive or activating agent therefor to the wall of a tubular container shell, for forming ribs in the container shell, for impregnating a lap joint of the shell 65 to render the same moisture proof, for supporting the container during the fabricating process, and for sealing the same after the contents have been placed therein.

Although only a single embodiment of the in- 75

vention has been illustrated in the accompanying drawings, it is to be expressly understood that various changes, many of which have been suggested in the foregoing description, may be made therein. The ribs 17, 17' for example, may be either continuous or interrupted and the term "rib," wherever used in the foregoing description or in the appended claims, is to be construed broadly enough to cover either a continuous or an interrupted groove. Many other changes, such as in the design, arrangement and size of the illustrated component parts of the container and of the means for carrying out the methods, as well as in the materials specified, may be made without departing from the spirit and scope of the invention, as will now be apparent to those skilled in the art. For a definition of the limits of the invention, reference will be had primarily to the appended claims.

0 What is claimed is:

1. The method of fabricating a container which includes making a shell having straight wall portions joined by arcuate wall portions, forming ribs in said straight wall portions by the operation of cooperating internal and external die members, and simultaneously forming ribs in said arcuate wall portions and forcing said straight wall portions outwardly into firm engagement with the faces of supporting die members. 5
2. The method of fabricating a container which includes making a shell having straight wall portions joined by arcuate wall portions, forming inwardly directed ribs in said straight wall portions intermediate the ends thereof, and exerting pressure against said arcuate wall portions to simultaneously form inwardly directed ribs and hold said straight wall portions outwardly in firm engagement with the faces of supporting die members. 10
3. The method of fabricating a container which includes making a shell comprising fibrous materials and having straight wall portions joined by arcuate wall portions, forming internal ribs and complementary external grooves in said straight wall portions, forming an internal rib and complementary external groove in each of said arcuate portions by the operation of converging linearly moving die members while holding said straight wall portions against outward bending. 15
4. The method of fabricating containers which includes making a tubular body comprising fibrous material and having straight wall portions connected by arcuate wall portions, and simultaneously exerting oppositely directed pressures against said arcuate wall portions tending to bend said straight wall portions outwardly and holding said straight wall portions against bending outwardly while inserting a closure in said body. 20
5. The method of fabricating containers which includes making a tubular body comprising fibrous material and having straight wall portions connected by arcuate wall portions, and simultaneously exerting oppositely directed pressures against said arcuate wall portions tending to bend said straight wall portions outwardly and holding said straight wall portions against bending outwardly while subjecting the marginal portion of the body to a curling action. 25
6. The method of fabricating containers which includes making a tubular body comprising fibrous material and having straight wall portions connected by arcuate wall portions, and simultaneously exerting oppositely directed pressures against said arcuate wall portions tending to bend said straight wall portions outwardly and holding said straight wall portions against bending outwardly while inserting a flanged closure into said body and curling the marginal portion 10 of said body into overlapping relation with the flange of said closure to form a closure seam. 30
7. The method of fabricating containers which includes making a tubular body comprising fibrous materials and having straight and arcuate wall portions, forming inwardly extending ribs in said straight wall portions adjacent an end of the body, applying an activated adhesive to the inner surface of said body adjacent said ribs, exerting pressure against said arcuate wall portions to form internal ribs therein and cause said straight wall portions to tend to bulge outwardly, inserting a flanged closure in said body against said ribs with the flange thereof engaging the activated adhesive, curling the marginal portion of the body into overlapping relation with said flange while holding said body against movement by means extending into grooves complementary to said ribs, and applying pressure to said marginal portion and flange to press the same into intimate contact and press said adhesive into the interstices of the engaging surfaces. 35
8. The method which includes making a blank comprising a layer of fibrous material and a layer of foil adhesively secured together, coating said foil layer with a dry film of lacquer having adhesive properties, making a laminated, foil-lined tubular body having straight wall portions joined by arcuate wall portions by adhesively joining the overlapping ends of said blank to form a lap joint, securing a paraffin coated strip to a second blank, adhesively securing said blank to said first-named blank, with said strip in contact with said joint and applying heat and pressure to melt said paraffin and cause the same to impregnate the ends of the fibrous material of said first-named blank, forming internal ribs in said straight wall portions, applying a liquid to a peripheral portion of the inner surface of said body to activate said lacquer by means having rolling contact with said surface, simultaneously forming an internal rib in each of said arcuate wall portions by the operation of converging, linearly moving die members while holding said straight wall portions against outward bending, inserting a flanged closure in said body against said rib with the flange thereof in close fitting engagement with the inner surface of said body and said activated adhesive, holding said body against longitudinal movement by means comprising a portion extending into grooves complementary to said ribs and having the operative face thereof inclined to the longitudinal axis of said body while curling the marginal portion of the body into overlapping relation with the flange of said closure, and pressing the engaging surfaces of said flange and the wall of said shell into intimate contact with each other. 40
9. The method which includes making a blank comprising a layer of fibrous material and a layer of foil adhesively secured together, coating said foil layer with a dry film of lacquer having adhesive properties, making a laminated, foil-lined tubular body having straight wall portions joined by arcuate wall portions by adhesively joining the overlapping ends of said blank to form a lap joint, securing a paraffin coated strip to a second blank, adhesively securing said blank to said first-named blank, with said strip in contact with said joint and applying heat and pressure to melt said paraffin and cause the same to impregnate the ends of the fibrous material of said first-named blank, forming internal ribs in said straight wall portions, applying a liquid to a peripheral portion of the inner surface of said body to activate said lacquer by means having rolling contact with said surface, simultaneously forming an internal rib in each of said arcuate wall portions by the operation of converging, linearly moving die members while holding said straight wall portions against outward bending, inserting a flanged closure in said body against said rib with the flange thereof in close fitting engagement with the inner surface of said body and said activated adhesive, holding said body against longitudinal movement by means comprising a portion extending into grooves complementary to said ribs and having the operative face thereof inclined to the longitudinal axis of said body while curling the marginal portion of the body into overlapping relation with the flange of said closure, and pressing the engaging surfaces of said flange and the wall of said shell into intimate contact with each other. 45
10. The method which includes making a blank comprising a layer of fibrous material and a layer of foil adhesively secured together, coating said foil layer with a dry film of lacquer having adhesive properties, making a laminated, foil-lined tubular body having straight wall portions joined by arcuate wall portions by adhesively joining the overlapping ends of said blank to form a lap joint, securing a paraffin coated strip to a second blank, adhesively securing said blank to said first-named blank, with said strip in contact with said joint and applying heat and pressure to melt said paraffin and cause the same to impregnate the ends of the fibrous material of said first-named blank, forming internal ribs in said straight wall portions, applying a liquid to a peripheral portion of the inner surface of said body to activate said lacquer by means having rolling contact with said surface, simultaneously forming an internal rib in each of said arcuate wall portions by the operation of converging, linearly moving die members while holding said straight wall portions against outward bending, inserting a flanged closure in said body against said rib with the flange thereof in close fitting engagement with the inner surface of said body and said activated adhesive, holding said body against longitudinal movement by means comprising a portion extending into grooves complementary to said ribs and having the operative face thereof inclined to the longitudinal axis of said body while curling the marginal portion of the body into overlapping relation with the flange of said closure, and pressing the engaging surfaces of said flange and the wall of said shell into intimate contact with each other. 50
11. The method which includes making a blank comprising a layer of fibrous material and a layer of foil adhesively secured together, coating said foil layer with a dry film of lacquer having adhesive properties, making a laminated, foil-lined tubular body having straight wall portions joined by arcuate wall portions by adhesively joining the overlapping ends of said blank to form a lap joint, securing a paraffin coated strip to a second blank, adhesively securing said blank to said first-named blank, with said strip in contact with said joint and applying heat and pressure to melt said paraffin and cause the same to impregnate the ends of the fibrous material of said first-named blank, forming internal ribs in said straight wall portions, applying a liquid to a peripheral portion of the inner surface of said body to activate said lacquer by means having rolling contact with said surface, simultaneously forming an internal rib in each of said arcuate wall portions by the operation of converging, linearly moving die members while holding said straight wall portions against outward bending, inserting a flanged closure in said body against said rib with the flange thereof in close fitting engagement with the inner surface of said body and said activated adhesive, holding said body against longitudinal movement by means comprising a portion extending into grooves complementary to said ribs and having the operative face thereof inclined to the longitudinal axis of said body while curling the marginal portion of the body into overlapping relation with the flange of said closure, and pressing the engaging surfaces of said flange and the wall of said shell into intimate contact with each other. 55
12. The method which includes making a blank comprising a layer of fibrous material and a layer of foil adhesively secured together, coating said foil layer with a dry film of lacquer having adhesive properties, making a laminated, foil-lined tubular body having straight wall portions joined by arcuate wall portions by adhesively joining the overlapping ends of said blank to form a lap joint, securing a paraffin coated strip to a second blank, adhesively securing said blank to said first-named blank, with said strip in contact with said joint and applying heat and pressure to melt said paraffin and cause the same to impregnate the ends of the fibrous material of said first-named blank, forming internal ribs in said straight wall portions, applying a liquid to a peripheral portion of the inner surface of said body to activate said lacquer by means having rolling contact with said surface, simultaneously forming an internal rib in each of said arcuate wall portions by the operation of converging, linearly moving die members while holding said straight wall portions against outward bending, inserting a flanged closure in said body against said rib with the flange thereof in close fitting engagement with the inner surface of said body and said activated adhesive, holding said body against longitudinal movement by means comprising a portion extending into grooves complementary to said ribs and having the operative face thereof inclined to the longitudinal axis of said body while curling the marginal portion of the body into overlapping relation with the flange of said closure, and pressing the engaging surfaces of said flange and the wall of said shell into intimate contact with each other. 60
13. The method which includes making a blank comprising a layer of fibrous material and a layer of foil adhesively secured together, coating said foil layer with a dry film of lacquer having adhesive properties, making a laminated, foil-lined tubular body having straight wall portions joined by arcuate wall portions by adhesively joining the overlapping ends of said blank to form a lap joint, securing a paraffin coated strip to a second blank, adhesively securing said blank to said first-named blank, with said strip in contact with said joint and applying heat and pressure to melt said paraffin and cause the same to impregnate the ends of the fibrous material of said first-named blank, forming internal ribs in said straight wall portions, applying a liquid to a peripheral portion of the inner surface of said body to activate said lacquer by means having rolling contact with said surface, simultaneously forming an internal rib in each of said arcuate wall portions by the operation of converging, linearly moving die members while holding said straight wall portions against outward bending, inserting a flanged closure in said body against said rib with the flange thereof in close fitting engagement with the inner surface of said body and said activated adhesive, holding said body against longitudinal movement by means comprising a portion extending into grooves complementary to said ribs and having the operative face thereof inclined to the longitudinal axis of said body while curling the marginal portion of the body into overlapping relation with the flange of said closure, and pressing the engaging surfaces of said flange and the wall of said shell into intimate contact with each other. 65
14. The method which includes making a blank comprising a layer of fibrous material and a layer of foil adhesively secured together, coating said foil layer with a dry film of lacquer having adhesive properties, making a laminated, foil-lined tubular body having straight wall portions joined by arcuate wall portions by adhesively joining the overlapping ends of said blank to form a lap joint, securing a paraffin coated strip to a second blank, adhesively securing said blank to said first-named blank, with said strip in contact with said joint and applying heat and pressure to melt said paraffin and cause the same to impregnate the ends of the fibrous material of said first-named blank, forming internal ribs in said straight wall portions, applying a liquid to a peripheral portion of the inner surface of said body to activate said lacquer by means having rolling contact with said surface, simultaneously forming an internal rib in each of said arcuate wall portions by the operation of converging, linearly moving die members while holding said straight wall portions against outward bending, inserting a flanged closure in said body against said rib with the flange thereof in close fitting engagement with the inner surface of said body and said activated adhesive, holding said body against longitudinal movement by means comprising a portion extending into grooves complementary to said ribs and having the operative face thereof inclined to the longitudinal axis of said body while curling the marginal portion of the body into overlapping relation with the flange of said closure, and pressing the engaging surfaces of said flange and the wall of said shell into intimate contact with each other. 70

GEORGE ARLINGTON MOORE.
